CLAIM

The ornamental design for a set of electrical contact pads as shown and described.

DESCRIPTION

FIG. 1 is a top right, front perspective view of a set of electrical contact pads according to a new design.

FIG. 2 is a top left, rear perspective view of the set of electrical contact pads of FIG. 1.

FIG. 3 is a bottom right, front perspective view of the set of electrical contact pads of FIG. 1.

FIG. 4 is a bottom left, rear perspective view of the set of electrical contact pads of FIG. 1.

FIG. 5 is a front view of the set of electrical contact pads of FIG. 1.

FIG. 6 is a rear view of the set of electrical contact pads of FIG. 1.

FIG. 7 is a first side view of the set of electrical contact pads of FIG. 1.

FIG. 8 is a second side view of the set of electrical contact pads of FIG. 1.

FIG. 9 is a top view of the set of electrical contact pads of FIG. 1; and,

FIG. 10 is a bottom view of the set of electrical contact pads of FIG. 1.

The broken lines in the drawings depict portions that form no part of the claimed design.
